PATRICK J. LUCEY, OF DETROIT, MICHIGAN, ASSIGNOR, BY MESNE ASSIGNMENTS, TO DAYTON SCALE COMPANY, OF DAYTON, OHIO, A CORPORATION OF NEW JERSEY

ARTICLE SUPPORTING DEVICE FOR SLICING MACHINES

Application filed April 29, 1929. Serial No. 358,918.

This invention relates to slicing machines, and it has to do especially with supporting and feeding mechanism for the article which is being sliced.

5 The invention is concerned particularly with slicing machines of the type which embodies a gauge plate, a rotating disc knife, and an article supporting carriage which is reciprocable generally in the plane of the 10 gauge plate and disc knife, to move the article past the cutting edge of the knife, and in which the article being sliced is held with some pressure up against the gauge plate and a guard for the knife. In this type of 15 machine, the article support ordinarily consists of a tray, and as the article is sliced, it slides on the tray step by step with its end remote from the knife, gradually approaching the same. This movement of the article 20 may be accomplished either by pressure of the hand of the operator, by a spring, or by mechanical means. This sliding of the article on the tray offers no material difficulty where 25 relatively solid articles are sliced, such as cured meats, sausages, or bread; however, in the case of relatively soft foods such as, certain kinds of fresh meat, the article cannot be readily slid along the tray without an undue distortion of the article which results in non- 30 uniform slices.

Accordingly, the present invention contemplates a slicing machine of the character mentioned, wherein a movable support is provided for the articles, and preferably this 35 support is removably mounted so that it may be used with soft easily distortable articles of food and not used where the food sliced is relatively solid.

In the accompanying drawings:

40 Fig. 1 is a somewhat diagrammatic view of an entire slicing machine, illustrating the same in plan and showing soft food support.

Fig. 2 is a side elevation looking from the right hand side of Fig. 1, showing the soft 45 food support in place and illustrating the same in dotted lines as removed.

Fig. 3 is a detail partly in section, in illustration of some of the detail construction.

50 The slicing machine comprises a body or support 1, a disc knife 2, disposed in a housing

3 and covered substantially entirely, except for the exposed cutting edge, and which may be driven by a suitable motor 4. A gauge plate 5 is in general alignment with the disc knife and this is adjustable by suitable means 55 (not shown) from right to left for determining slice thickness. Suitable rail devices 6 are mounted on the support and a carriage 7 is reciprocably mounted upon the rails, and such reciprocation may be effected in any de- 60 sirable way, as by means of handle 8.

This carriage comprises a tray 9, advantageously of V shape, as illustrated in Fig. 2, and the article to be sliced is placed in the tray. It is well understood that as the carriage 65 is reciprocated, a slice is severed from the article each time the same moves across the cutting edge of the knife from the gauge plate to the knife, and following each severing of a slice, the article is moved by a sliding action on the tray so as to be in position 70 for the next slice. There is shown herein, a follower mechanism for so moving the article as it is sliced, which corresponds to that shown in co-pending application Serial No. 75 322,207, filed November 27, 1928. This mechanism may be described only generally herein. It comprises a follower plate 10 journaled in an arm 11, which is in turn journaled as at 12. The arm may be moved out of the 80 way so that it can be used or not used, as illustrated by the dotted lines in Fig. 2.

The journal 12 is afforded by a fixture 13 which is slidable upon rods 14 and 15. These rods extend in a direction at right angles to 85 the rails 6 so that the follower can move up to the disc knife and gauge plate, pushing the food before it. It may be pushed by hand, also it may be pushed by a spring arrangement which comprises a coil spring 20 which 90 encircles a rod 21, in turn carried by brackets 22. The spring is covered by a tube 24 and by a tube 25, which telescopes over tube 24, as shown.

One end of the tube 25 engages the end of 95 the spring 20 and upon this tube is carried a controlling handle 26, supported as by means of a suitable collar 27. Projecting from this handle is a lug 28 (Fig. 2). The handle 26 is rockable, and it may be retracted 100

away from the disc knife by compression of the spring 20, and then it may be rocked counterclockwise (Fig. 2) to hook the lug 28 behind the pusher plate bracket 13. Thus the spring 20 exerts an expanding tendency and causes the follower plate 10 to push the article along the tray and against the disc knife.

Bracket 13 has lugs, or supporting devices 30 which are designed to support a removable 10 food-carrying element 31. This element is angular in formation to fit the shape of the V-shaped tray, and the same is provided with devices such as hooks 32, for fitting over the lugs 30. The food support 31 may also be 15 provided with a multiplicity of pins 33 for impinging into the article to be sliced, and the same is also preferably provided with nubs, or projections 35 for resting upon the food-supporting tray and to slide thereon. 20 When an article of soft, or distortable food-stuffs is sliced, the auxiliary support 31 may be quickly placed into position by merely hooking the same on the lugs 30, whereupon the article to be sliced may be merely placed 25 on this auxiliary support. Inasmuch as the support is carried by the advancing bracket 31, the soft foodstuffs is carried forward by the auxiliary support, and the pressure for this purpose may be obtained either by hand 30 or by utilizing the spring 20.

When the auxiliary supporting tray is used, it is, of course, not necessary to employ the follower plate, inasmuch as the article to be sliced is carried on the movable auxiliary support, in which event, the follower plate 10 may be moved out of the way approximating the position illustrated by the dotted lines in Fig. 2.

I claim:

- 40 1. In a slicing machine, the combination of a rotating disc knife, a gauge plate, a carriage mounted for reciprocation across the face of the knife and plate, an article-supporting tray on the carriage for supporting 45 an article to be sliced, means mounted on the carriage movable toward and away from the knife, and an auxiliary article support removably secured to said means and arranged to overlie the tray.
- 50 2. In a slicing machine, the combination of a rotating disc knife, a gauge plate, a carriage mounted for reciprocation across the face of the knife and plate, an article-supporting tray on the carriage for supporting 55 an article to be sliced, means mounted on the carriage movable toward and away from the knife, an auxiliary article support removably secured to said means and arranged to overlie the tray, and means on said auxiliary 60 support for slidably engaging the tray.
- 65 3. In a slicing machine, the combination of a rotating disc knife, a gauge plate, a carriage mounted for reciprocation across the face of the knife and plate, a V-shaped article-supporting tray on the carriage for sup-

porting an article to be sliced, means mounted on the carriage movable toward and away from the knife, and a V-shaped auxiliary article support removably secured to said means and arranged to overlie the tray, and means 70 on said auxiliary support for slidably engaging the tray.

4. In a slicing machine, the combination of a disc knife, a gauge plate, a reciprocable carriage movable across the face of the plate and knife, an article-supporting tray thereon, means on the carriage movable toward and away from the knife, including a follower for urging an article slidably along the tray, means movably mounting the follower, 75 whereby the same may be moved away from the tray, and an auxiliary article support removably attached to the first mentioned means.

5. In a slicing machine, the combination of a disc knife, a gauge plate, a reciprocable carriage movable across the face of the plate and knife, an article-supporting tray thereon, means on the carriage movable toward and away from the knife, including a follower 90 for urging an article slidably along the tray, means movably mounting the follower, whereby the same may be moved away from the tray, an auxiliary article support removably attached to the first mentioned means, 95 and a spring-pressed advancing element capable of urging the first mentioned means towards the gauge plate and knife.

In testimony whereof I affix my signature.

PATRICK J. LUCEY.
